WEB FEED APPARATUS

Robert F. Hollis, Alton, Ill., assignor to Alton Box Board Company, Alton, Ill., a corporation of Delaware

Application March 14, 1957, Serial No. 646,120

4 Claims. (Cl. 271—2.2)

This invention relates to machinery for the substantially continuous processing of a web.

The apparatus of this invention will be described in connection with the processing of paperboard. It is to be understood however, that the device has application to any web of sheet material such as plastic, rubber, steel, brass, various metal foils, and the like.

In a rotary printer and blanker for paperboard box-making machines, a web of paperboard is pulled from a large unwind roll of paperboard. As one unwind roll is exhausted, a new one is put into position and the free web end of the new roll is joined to the old web. The printers and blankers are so constructed that a lap splice cannot be used to join the two webs; they must be butt spliced. It is not only highly desirable but practically essential in modern high speed machines that some sort of arrangement be made which will permit the printer and blanker to be operated while the splice is being made, so that the printing and blanking machinery does not have to be stopped and started again.

Heretofore devices have been used which are exemplified by Figure 1 of a patent to E. E. Garrett, No. 2,606,136. Typically, these prior art devices have utilized a free loop of web between the unwind roll and feed rolls to the press unit to separate the press unit from the splicer and storage device, which in Garrett takes the form of a tower. None of these prior art devices has been capable of operating at the full speed at which printer and blanker units can be run. For example, if the full rated speed is 960 feet per minute, the machine has had to be slowed to about 200 feet per minute in order to accommodate the splicer and storage units. The free loop in the device known heretofore has given rise to difficult tracking problems since the web is necessarily uncontrolled when there is no tension in it.

One of the objects of this invention is to provide an infeed device capable of permitting continuous operation, at full speed, of web processing machinery on one side of the infeed device, and intermittent processing of the web on the other side of the infeed device, and at the same time to maintain, on the continuous operating side of the device, a constant, substantially uniform tension in the web.

Other objects will become apparent to those skilled in the art in the light of the following description and accompanying drawing.

In accordance with this invention generally stated, an infeed device is provided with a multiplicity of vertically floating rolls around the underside of successive of which a web passes. The floating rolls are gravity biased by one or more weights meditately connected to the rolls by springs in such a way as to permit limitedly independent motion of the individual rolls. The arrangement of weights and springs is such as to damp out any pulses present in the web when it reaches the infeed device, and to impart to the web a constant, substantially uniform tension by the time it leaves the infeed device.

A control connected to respond to vertical travel of

2

the floating rolls, regulates the input of web to the infeed device, to restore the rolls to a preset "zero" position when they have moved in response to a tension imbalance in the web.

5 In the drawing:

Figure 1 is a view in side elevation, diagrammatic in character, of an illustrative embodiment of an infeed device of this invention in a web processing apparatus;

Figure 2 is an enlarged sectional view in side elevation 10 of the infeed device of this invention shown in Figure 1;

Figure 3 is a sectional view taken along the line 3—3 of Figure 2;

Figure 4 is a fragmentary sectional view taken along the line 4—4 of Figure 2;

15 Figure 5 is a fragmentary sectional view taken along the line 5—5 of Figure 4; and

Figure 6 is a fragmentary, somewhat diagrammatic view in side elevation of the device of this invention in the course of responding to a tension imbalance in the web.

20 Referring now to the drawing for an illustrative embodiment of this invention, reference numeral 1 indicates an infeed unit constructed in accordance with an illustrative embodiment of this invention. The infeed unit 1 is positioned between an automatic splicer 2 and the first unit of a rotary paperboard box printing press 3.

25 In the illustrative application of this unit shown in the drawings, a web of paperboard 5 is pulled from an unwind roll 7 mounted on reel stand 9. In the situation shown in Figure 1, the unwind roll 7 from which the web 5 has been pulled is nearly exhausted and a second web 5' is being spliced to the web 5 from a fresh unwind roll 7'. The web or webs tend from the unwind roll through guide rolls 11 and through the splicer 2. Immediately beyond the splicer 2 are primary infeed pull rolls 15. From the primary infeed rolls 15 the web enters the unit 1. The web is pulled from the unit 1 by press pull rolls 17.

30 As shown in Figures 1 and 2, the web leaving the unit 1 and entering the rotary press 3 is under tension. That is to say, there is no loop of untensioned web between the unit and the press pull rolls 17 or between the press pull rolls 17 and the press 3.

35 The infeed unit 1 in the embodiment shown is supported by a stanchion 20 made up of legs 21 connected by a horizontal beam 22. The stanchion 20 carries a box frame 24 made up of a pair of horizontally spaced bottom rails 26 connected by bottom end rails; upright columns 28 at the ends of the bottom rails 26; a pair of horizontally spaced upper rails 30; and upper end rails 50 between the ends of the upper rails 30. Center columns 32 rest on the cross-beam 22, and extend above the upper rails 30. A cross-bar 36 extends between the center columns 32 at the level of the upper rails 30.

40 55 Each of the columns 32 carries on its upper end a pillow block 40 in which a shaft 42, carrying a crowned roll 44, is journaled.

55 60 The center column 32 divides the infeed unit 1 into two sections, which will be called the right section 45 and the left section 47. Along each of the upper rails 30 in each of the right sections 45 and left sections 47 are nine pillow blocks 50.

65 Extending between the upper rails 30 and the lower rails 26, on center below the pillow blocks 50 are spaced guide rails 55. The guide rails 55 are formed with feather keys 57, as shown particularly in Figure 5. Floating bearing blocks 59, splined to take the keys 57, are mounted between adjacent guide rails 55 for free vertical movement. Rubber jam pads 61 are mounted between the guide rails 55 directly under the upper rails 30 and directly above the lower rails 26 to cushion the

bearing blocks 59 when they reach the limits of their travel.

Crowned idler rolls 64, shafts 65 of which are journaled in the pillow blocks 50, lie parallel with one another between the upper rails 30. Crowned floating rolls 71 through 86, each with a long spindle 88 journaled for rotation in opposite splined bearing blocks 59, lie parallel with one another and parallel with the rolls 64 but below and in staggered relation to the rolls 64. A left section guide roll 90 is mounted for rotation below and between the lower rails 26 directly below the roll 64 next to the center column 32 in the left section 47. A right section guide roll 91, mounted for rotation between and below the lower rails 26, lies directly below the roll 64 next to the center column 32 in the right section 45.

Each of the spindles 88 of the rolls 71 through 86 projects beyond its bearing 59 on either side and carries on each of its projecting ends a link-carrying bearing 93, from which a link 95, in the form of an eye bolt, depends. A spring 97 hangs from each of the links 95.

All of the rolls 71 through 86 are inter-connected meditately, the links 95 and springs 97 being the last or quaternary stage, in the overall linkage system.

The springs carried by the spindles of the rolls 71 and 72 are connected to the opposite ends of a quaternary or Q-link 101. Rolls 73 and 74 are coupled through a Q-link 103; rolls 75 and 76, through a Q-link 105; rolls 77 and 78 through a Q-link 107; rolls 79 and 80 through a Q-link 109; rolls 81 and 82 through a Q-link 111; rolls 83 and 84 through a Q-link 113; and rolls 85 and 86 through a Q-link 115. Springs 117 are pivotally suspended from the center of each of the Q-links and in turn support tertiary links, to which they are pivotally connected at the ends of the tertiary links. Thus, Q-links 101 and 103 are coupled to the ends of a tertiary or T-link 121; Q-links 105 and 107 are coupled to a T-link 123; Q-links 109 and 111, to T-link 125 and Q-links 113 and 115, to T-link 127. A spring 129 is pivotally suspended from the center of each of the T-links. The spring 129 suspended from the T-link 121 is pivotally connected to one end of a secondary or S-link 131, to the other end of which the spring 129 from the T-link 123 is pivotally connected. Similarly, the springs 129 from the T-links 125 and 127 are connected to opposite ends of an S-link 133. A spring 135 is pivotally suspended from the center of each of the S-links 131 and 133. The springs 135 are pivotally connected to opposite ends of a primary link 137.

In the embodiment shown, weights 139, in the form of lead plates, are bolted to each of the primary links 137 in such a way that the weights can be shifted lengthwise of the link 137 to balance the link 137.

A cross-bar 141 is rigidly secured to the two primary links 137 at their centers. Weights 143 are bolted to the cross-bar 141 in such a way as to be shiftable to balance the two linkage systems to level the rolls 71 through 86.

The cross-bar 141 is connected by means of a flexible cable 145 to a sensing device or level control 147. The sensing device 147 which, in the embodiment shown, is mounted on one leg 21 of the stanchion 20, may be a standard commercial device of the character of the differential transformers, sold under the trade-names "Atco-tran" and "VSS." Such differential transformers sense not only a change in vertical position of the cross-bar 141 but the amount of that change. The sensing device 147 is connected through its circuit 148, shown diagrammatically, to a motor 149 which drives the primary infeed pull rolls 15. In the embodiment shown, the motor 149 drives the pull rolls 15 positively through gears 151. In practice, the travel of the flexible cable 145 is too great for direct connection to the differential transformer, and suitable proportional reduction is provided.

The travel of the web through the unit 1 is as follows: From the splicer 2, the web 5 extends below the lower of the pull rolls 15, makes a turn of 180° around the

roll and passes through the nip between the pull rolls 15. From the nip of the pull rolls 15 the web extends substantially vertically past the guide roll 90 to the upper roll 64 next to the center column 32 in the left section 47 of the unit 1. The web makes a turn of 180° around the roll 64 and passes down around the lower half of the floating roll 71; thence up to the next upper roll 64 and down to the floating roll 72 and so on until, after leaving the floating roll 78, it passes around the outside of the roll 64 farthest from the center roll 62 in the left section 47. From there the web extends over the top of the center column roll 44 to the top of the roll 64 farthest from the center column 32 in the right section 45; thence down around the floating roll 79, up to the next roll 64 and so on until it passes around the roll 64 next to the center column 32 in the right section 45. From that roll 64 the web passes along the guide roll 91 to the press pull roll 17.

While as has been pointed out heretofore, the illustrative application shown and described herein is only one of many in which the device of this invention may be used and the dimensions even of a unit for use with paperboard may be varied, the following description of the operation of the device illustrated will be described with reference to a specific unit in a specific situation to illustrate just what can be accomplished by the use of the device.

In the following description, the device will be assumed to have the following dimensions: the upper and lower rails are about 12 feet long and are spaced vertically 5 feet. Thus, each of the sections 45 and 47 is 6 feet long and 5 feet high. The rails 26 and 30 are spaced horizontally approximately 3½ feet. The rolls 64 and 71 through 86 are approximately 6½ inches in diameter at their crowns, and are mounted on 8 inch centers. They are preferably made of aluminum and weigh approximately 35 pounds apiece.

The weights 139 and 143 total approximately 300 pounds.

The web 5 of paperboard from unwind roll 7 is thirty-six inches wide. It will also be assumed that the roll 7 has been dropped so that it has in it humps which would normally interfere with its smooth feed into the printer, and the caliper of the paper varies. The web is being fed into the printer at the rate of 960 feet per minute. With the weight of the rolls 71 through 86, the floating bearing blocks 59, the linkage system and the weights 139 and 143, the tension on the web 5 when the system is in equilibrium, with the floating rolls 71 through 86 lifted above the jam pads 61 on the upper side of the rails 26, is approximately 50 pounds. In the normal running ("zero") position, the rolls 71 through 86 will be approximately 6 inches above the lower jam pads. The tension on the web through the infeed unit 1 is enough to ensure proper tracking over the crowned rollers in spite of the caliper variation. Generally, even a poor offset mill splice which may show up from the roll 7 will pass through the infeed unit without trouble because the low tension is insufficient to break the web at the splice.

The jerky feed from the humped roll 7 is smoothed out in only a few passes around the floating rolls. Floating rolls 71 through 78 will react with progressively decreasing violence and the subsequent rolls will be quiet as the pulses in the web are smoothed out by the action of the springs connected immediately and meditately to the rolls. Ordinarily, pulses and jolts will be damped by the first four rolls 71 through 74. Thus, even before the web leaves the left section 47 it will be feeding smoothly.

Assume now that the web 5 is being fed to the printer and blanker 3 at 960 feet per minute, and the system is in equilibrium. The unwind roll 7 is nearing exhaustion and a new roll 7' is swung into position with its web 5' tending from it. The feed from the press pull

rolls 17 continues at 960 feet per minute. The web 5' is put into position, through the rolls 11, into the splicer 2. The primary infeed pull rolls 15 are now stopped, a process which normally takes approximately two seconds. A butt splice is made by the splicer 2, which may be either semi-automatic or completely automatic. The splice is made while the webs 5 and 5' are stationary in the splicer 2. The splicing operation takes an additional two seconds. The primary infeed rolls 15 are then started up and brought up to speed, which requires another two seconds. So far as the press pull rolls 17 are concerned, there has been no change during the entire process, because the web has been feeding out of the unit at full speed and at substantially the equilibrium tension.

Within the infeed device, when the primary infeed rolls 15 are stopped, the floating rolls 86 through 79 begin to rise as indicated in Figure 6. During the splicing time, the rolls 86 through 79 progressively rise until they sequentially hit the jam pads 61 on the underside of the upper rails 30. As the floating roll 79 rises, the roll 78 in the left section 47 begins to rise and a similar pattern of sequential rising of the floating rolls 78 through 71 takes place.

As the primary infeed rolls 15 are again speeded up, the floating rolls will continue to rise until the primary infeed rolls have reached the same speed as the press pull rolls 17. The primary infeed rolls are then overdriven with respect to the press pull rolls 17, and the floating rolls will begin to move down in the reverse order from that in which they rose.

The overdrive of the primary infeed rolls 15 is controlled by the level control 147 and continued until the cross-bar 141 has reached its normal position, with the floating rolls about 6 inches above the lower jam pad, when the primary infeed rolls 15 are synchronized with the press pull rolls 17.

With the dimensions of the device given, approximately 128 feet of web can be stored, although, since the normal position of the floating rolls is about 6 inches from their lowest possible position, the capacity of the unit in practice is approximately 112 feet. The total time elapsing in the splicing operation is 6 seconds. Thus, with the web running at 960 feet per minute, 96 feet of web would be pulled from the infeed device if the primary infeed rolls were stopped instantaneously, and brought up to speed again instantaneously. Actually, since the primary infeed rolls slow down to stop and speed up to full speed during that six second period, only about 64 feet of web is pulled from the infeed device.

The splicing process can be made largely automatic. With suitable simple electrical circuits the operator need only press a "splice button" to start the sequence of steps just described, i.e., the slowing of the primary infeed rolls to a stop, the making of the splice and the bringing of the primary infeed rolls up to speed. The level control 147 is by-passed during three stages, but is put back into operation when the primary infeed rolls are brought up to speed. The level control 147 then takes over to speed the primary infeed rolls well beyond the normal feed speed, for example, 985 feet per minute. As the cross-bar 141 descends, the level control 147 gradually slows the motor 149 until, when the cross-bar 141 has reached the normal or zero position, the primary infeed rolls 15 have been brought smoothly into synchronization with the press pull rolls 17, and the floating rolls 71 through 86 are in equilibrium position.

It can be seen that since the total weight on the web through the infeed device remains constant, the floating rolls 71 through 86 being gravity biased, the tension on the web as it comes from the device must remain substantially constant. There will of course be some change while the floating rolls are in the process of moving vertically, but that change will be relatively small, since the

rolls themselves are made as light weight as possible, the springs take up any momentary jolts, and the floating rolls are free to rise and fall within their guideways.

If the press is slowed down for some reason, or even if the press is suddenly stopped dead, as in an emergency, the infeed device will act to keep the tension in the web constant at the press pull roll. Furthermore, unlike the complicated tower mechanism of gears and clutches of the prior art, the infeed unit of the present invention cannot be damaged by a very sudden stop. The primary infeed rolls 15 stop with the press, and their drive is built to withstand such a shock. There is nothing in the infeed unit itself to be damaged.

The fact that the printer and blanker may be operated continuously at a uniform speed and tension with the infeed unit of the present invention is of great importance, not only in that it allows for greater production in the same length of time, but also in that it eliminates many registry problems and the like which have resulted when the web has had to be slowed down for each splice. For example, register is affected by the change of rolling friction of the web on the intaglio cylinders. A constant speed eliminates this problem. At the same time, the device if this invention permits the splice to be made on a stationary web, which simplifies the design of the splicer and makes possible a strong, neat splice.

Numerous variations in the construction of the device of this invention within the scope of the appended claims will occur to those skilled in the art in the light of the foregoing disclosure. For example, the top rolls 64 need not be journaled in rigidly fixed bearings but may be spring suspended or otherwise cushioned to assist in the damping of pulses in the web, without interfering with the substantially uniform tension in the web resulting from the fact that the floating rolls 71 through 86 are gravity biased. One or more of the top rolls 64 may be equipped with a so-called tension dynamometer, so that the actual tension in the web may be checked. While the arrangement of linkages shown is the preferred one because the action of all the rolls is integrated, and controlled by one level control, the floating rolls in the right section 45 need not be connected to the floating rolls in the left section 47. The secondary links 131 and 133 may be provided with weights. Certain of the connecting springs can be eliminated. For example, the springs 135 may be replaced by solid links, because much of the work of damping will be accomplished by the springs 97 and 117. The number of rolls may be increased or decreased, and the rolls need not be divided into two sections, although the arrangement shown and described provides for a compact and efficient unit. If the linkage system shows a tendency to swing, guides can be provided to stabilize it.

In the illustrative embodiment shown, the process (splicing) on the incoming side of the infeed unit has been intermittent and the process (rotary printing and blanking) on the outgoing side of the infeed unit has been continuous. The character of the processes may be reversed, or the processes on both sides can be continuous or intermittent. In any event, the infeed device will serve a function if there is an opportunity for the process on one side to be unsynchronized with the process on the other side. If it is contemplated that the process on the outgoing side of the infeed unit is to be slowed or stopped with respect to the process on the incoming side of the infeed unit, then the normal or zero position of the floating rolls must be near the upper limit of travel of the floating rolls rather than near the lower limit of travel. In any event, the infeed device isolates the process on the outgoing side from the process on the incoming side while maintaining tension on the web sufficient to ensure proper tracking and control over the web.

Two or more of the infeed devices may be used in one line of machinery. For example, one infeed unit can be positioned between the unwind roll and the printing section of a rotary printer and blanker as has been

described, and another can be positioned between the printing section and blanking section, not only to damp the pulsations from the blanking section but to isolate the printing and blanking sections from one another so that the registry problems in the two sections can be handled independently.

The control of the tension in the web which is exercised by the level control may be exercised in any number of suitable ways. For example, a pull roll on the outgoing side can be speeded up to increase web tension, or rolls on the incoming side may be braked to accomplish the same result. The advantage of the preferred method, of controlling the speed of rotation of the primary infeed rolls, in the application shown lies in the fact that the press roll speed may be maintained constant, and no actual braking is necessary so that the problems of over-heating and grabbing of brakes is not encountered.

It can be seen that the particular linkage system of the illustrative example is only possible when there are sixteen floating rolls. By using a different number of rolls, the system can be "weighted" either in favor of or against particular sets of rolls. For example, if six floating rolls are used in the left section 47 and pairs of successive rolls are joined as in the illustrative embodiment, there will be three Q-links instead of four. If the two Q-links farthest from the center column 32 are connected by a T-link and that T-link is in turn connected to one end of an S-link, while the Q-link next to the center column 32 is connected directly to the other end of the S-link, the violent reaction of the two rolls next to the center column in response to pulses from the unwind roll will be reflected in the S-link and the primary link to a much greater degree than if the Q-link next to the center link were connected through a T-link to the next successive Q-link and the Q-link farthest from the center column 32 were connected directly to one end of an S-link. In the latter case the motion of the floating rolls next to the column 32 would be minimized as that motion is reflected in the primary link. The weighting is, of course, even greater when an odd roll is connected directly through its spring 97 to one end of a T or S-link. It can also be seen that to connect thirty-two floating rolls together in pairs, a set of quintary links must be provided, pairs of which will be connected to a quaternary link, and so on, but the principle of their operation is the same.

Numerous other variations in the construction and arrangement of the infeed device, within the scope of the appended claims, will be apparent to those skilled in the art in the light of the foregoing disclosure. For example, in order to facilitate feeding of the web through the infeed device, the spindles 88 of the rolls 71 through 86 may be extended beyond the link-carrying bearings 93 and provided at their ends with capsule bearings. The capsule bearings, one on each end of each spindle, are positioned to rest on top of an I beam when the I beam is elevated. The I beam is constructed and arranged to be elevated and lowered horizontally by means of jack screws driven by a reversible motor. Thus, when it is desired to thread the infeed device, it is only necessary to raise the beam by means of the jack screws until the beam contacts the capsule bearings and then, with continued elevation of the I beam, the rolls 71 through 86 will be raised to a position immediately below the upper rolls 64. The web can then easily be threaded through the infeed device, after which the I beam is lowered beyond the lowermost travel of the rolls 71 through 86 so as to be out of the way during the operation of the device.

Having thus described the invention, what is claimed and desired to be secured by Letters Patent is:

1. In a rotary paperboard printer wherein a web of paperboard is pulled from an unwind roll and a web of paperboard from a fresh unwind roll is spliced to the

5 web of paperboard from an exhausted unwind roll by a mechanical splicer while the printer continues to operate, the improvement comprising an infeed device, primary infeed pull rolls between the splicer and the infeed device, and press pull rolls between the infeed device and the printer, said infeed device comprising a multiplicity of rolls over which the web travels and between which the web hangs in loops, the number of rolls being such that 2^n loops are provided, n being an integer greater than one; vertical guide ways below said rolls; a floating roll resting on the web within each of the loops, said floating rolls being journaled in bearings slidably mounted in said guide ways to permit said rolls to float vertically, said floating rolls being biased downwardly solely by gravity, whereby the floating rolls respond to varying tension in the web by vertical translation, each of said floating rolls carrying on each of its ends a spring, the springs on each respective end of successive rolls being coupled to opposite ends of a link, said links in turn being coupled in pairs to another link, and so on until all of the floating rolls are inter-connected through a common link, the common links on both sides of the rolls being connected by a cross-bar; and a control responsive to change in position of the cross-bar and connected to control the speed of rotation of the primary infeed pull rolls, whereby when the cross-bar rises above a preset normal position the primary infeed pull roll is speeded up and vice versa, the vertical reach of the loops and the number of floating rolls being such that the infeed device contains a sufficient length of web to accommodate the demand of the printer during the splicing operation.

2. In a line of machinery wherein a web of material is processed at high speed, an infeed device, positioned intermediate the ends of the line, comprising a multiplicity of idler rolls over which the web travels in a single pass and between which the web hangs in loops; and a multiplicity of floating rolls, each resting on the web within one of the loops, said floating rolls being arranged to float vertically and being biased downwardly solely by gravity, each of said floating rolls carrying a spring at each end, the springs of each end respectively of successive rolls being connected to opposite ends of a common link, for limitedly independent movement of the individual rolls, whereby the floating rolls respond to varying tension in the web by vertical translation and whereby the tension imparted to the web by the floating rolls is the same at every position of the floating rolls when the tension in the web is in equilibrium.

3. In a line of machinery wherein a web of material is processed and in which the machinery in one part of the line is occasionally run at a different web speed than the machinery in another part of the line for a length of time which does not exceed a known maximum, an infeed device positioned between the machinery in the said two parts of the line, said infeed device comprising a multiplicity of idler rolls over which the web travels in a single pass and between which the web hangs in loops, there being at least four of said loops; a floating roll resting on the web within each of the loops, said floating rolls being arranged to float vertically and being biased downwardly solely by gravity whereby the floating rolls respond to varying tension in the web by vertical translation; and links, pivotally suspended from adjacent floating rolls, each of said links being suspended at only two, spaced points and each adjacent link being pivotally connected to and suspending a connecting link, each of said connecting links being suspended at only two, spaced points, whereby all of the said links and said floating rolls are pivotally interconnected, said floating rolls having sufficient vertical travel and being of sufficient number to provide storage for an amount of web at least equal to the product of the average difference between the speeds of the web through the machinery in the two parts of the line and the said maxi-

mum length of time during which said difference occurs.

4. In a line of machinery wherein a web of material is processed at high speed, an infeed device, positioned intermediate the ends of the line, comprising a multiplicity of idler rolls over which the web travels in a single pass and between which the web hangs in loops; a multiplicity of floating rolls, each resting on the web within one of the loops, said floating rolls being arranged to float vertically; links, pivotally suspended from said floating rolls, and connecting links, pivotally suspended from said floating roll-suspended links, each of said floating roll-suspended links carrying a connecting link, each of said floating rolls being connected to a

link, and all of said links being suspended at only two, spaced points.
